CARBURETOR

Fred E. Aseltine, Dayton, Ohio, assignor to Delco Products Corporation, Dayton, Ohio, a corporation of Delaware

Application May 31, 1930. Serial No. 457,695

13 Claims. (Cl. 261—49)

This invention relates to carburetors for internal combustion engines, and while a preferred form of the invention is shown herein as embodied in that type of carburetor which comprises a plurality of primary mixing chambers, each of which delivers a primary mixture of fuel and air to one of a plurality of secondary mixing chambers in which the primary mixture is mixed with additional air under certain operating conditions, it will be understood that the invention is not limited to that type of carburetor and is of entirely general application to any form of carburetor.

The device shown in the drawings is of exactly the same general construction as that shown in the copending application of Fred E. Aseltine et al., Serial No. 370,179, filed June 12, 1929, and reference is had thereto for a detailed description of the device.

The general purpose of the invention is to provide means for preventing enrichment of the mixture on deceleration occasioned by a rise in the level of fuel in the float chamber.

In carburetors in which the float is not concentrically arranged with respect to the float chamber and which are so mounted on the engine that the float lies to the rear of the axis of the float chamber, the float will drop, on deceleration to a position below that it should assume, admitting fuel to the float chamber until the level is higher therein than it should be, which results in too great a head on the fuel at the nozzles and too great a flow of fuel therefrom to form a mixture of proper proportions. The reason for this is seen in the surge of fuel toward the forward side of the fuel bowl with respect to the vehicle. When the operator takes his foot from the accelerator on deceleration, the throttle is automatically closed and the slowing down of the vehicle causes the fuel to surge toward the front side of the fuel bowl, lowering the level of the fuel on the rear side where the float is positioned. This action permits the float to drop, opening the fuel inlet to the fuel bowl wide and permitting fuel to flow rapidly into the float chamber until the fuel level rises sufficiently to close the float valve. This action raises the level of the fuel in the float chamber above the normal, resulting in the enrichment of the mixture above referred to.

According to the present invention, this objectionable action is overcome by providing means operated by the throttle as it is closed, which holds the float up, preventing the admission of fuel as described.

Further objects and advantages of the present invention will be apparent from the following description, reference being had to the accompanying drawings wherein a preferred embodiment of one form of the present invention is clearly shown.

In the drawings:

Fig. 1 is a side elevation of a carburetor, partly in section, constructed in accordance with this invention.

Fig. 2 is a section on the line 2—2 of Fig. 1, partly broken away to show certain parts in elevation and omitting certain parts.

Fig. 3 is a side elevation showing certain parts in section.

The drawings illustrate a carburetor unit which is adapted to be used with an intake manifold of the specific construction shown in application Serial No. 370,179 of Aseltine et al., filed June 12, 1929. This carburetor unit comprises a main housing 10, an air intake coupling 12 adapted to admit air thereto and a casting 14 secured to the bottom of the main housing in any desirable way. The latter having various fuel passages and dashpot chambers formed therein as in the above application. The main housing is provided with an annular shoulder 16 against which a sheet metal float chamber 18 is held tight by a screw 20 screwed into the casting 14. Fuel is admitted through a passage controlled by a valve, as shown in Fig. 3. The fuel valve is controlled by a float 22, which, as clearly shown in Fig. 2, lies to the right of the axis of the float chamber and toward the rear of the vehicle on which the carburetor is used.

Fuel is conducted from the main fuel tank to horizontal fuel channel 23 formed in the carburetor casting. This channel connects with a vertical fuel channel 25, having an enlarged lower end in which is a nipple 27, provided with a restriction 29, forming a seat for a fuel valve 31, resting on an arm 33, projecting from the float 22 and pivoted on the pin 35 mounted on one of the carburetor castings. This mechanism is more fully described in the above mentioned application.

Fuel is supplied from the float chamber to fuel nozzles 24, located in primary mixing chambers 26, through a conduit formed in the casting 14 and air is supplied thereto through the coupling 12, which is controlled by a suction operated air valve 27, secured to a valve stem 28, normally held closed by a spring 29, received between the valve and a flange 30 on a slideable sleeve 32, which may be lifted by a choke lever 34 to hold

the valve closed to facilitate starting, all of which is fully shown and described in the above application.

The air valve 27 admits air to a main air chamber 36 from which it flows to the primary mixing chambers and to the secondary mixing chambers, the flow of air to the secondary mixing chambers being controlled by a secondary throttle secured to a shaft 40 journalled in the main housing, 5 which is operated by a primary throttle 41 through the medium of an operating link 42 connected to an arm 44, secured to the shaft 40, and to an operating plate 46 secured to one end of said primary throttle as fully described in said earlier 10 application. The operating plate 46 is rotated in a clockwise direction, as viewed in Fig. 1, on opening of the primary throttle and in the reverse, or counter-clockwise direction on closing of said throttle.

20 Pivotedly connected to an ear 48 projecting from the operating plate 46, is a rod 50, which at its lower end extends into a tube 52 closed at the bottom and projecting upwardly from the piston 54 of a fuel pump which is slidable in a pump cylinder 56, this pump being operated on every 25 opening movement of the primary throttle to supply additional fuel to the primary mixing chambers during the acceleration period as fully set forth in the earlier application.

30 Secured to the piston rod by brazing or otherwise, and extending laterally therefrom is an ear 58 to which is secured by the screw 60, an angular flat bar 62 formed of sheet metal. This bar comprises a portion 64 extending from its point of attachment to the ear 58 toward the rear of the carburetor, a lateral portion 66 extending transversely of the carburetor as shown in Fig. 2, a portion 68 which projects downwardly from the lateral part 66 and connects with a forwardly extending portion 70, which lies immediately beneath the float 22.

35 When the parts are in the position shown in the drawings with the throttle closed, the part 70 of the bar 62 occupies a position such that the float will not be allowed to drop more than enough to permit the fuel valve operated thereby to open more than enough to permit just enough fuel to flow into the float chamber to satisfy the demands of the engine when running very slowly under load, or idling. As the throttle is opened, the bar is lowered away from the float so that 40 opening of the float is controlled entirely by the level of liquid within the float chamber. When the throttle is closed, however, the bar lifts up the float so that it is almost closed for the purpose 45 previously described. This mechanism is particularly useful to prevent enriching of the mixture when the vehicle is stopped suddenly by use of the brake. When the operator's foot is removed from the foot accelerator pedal and the 50 brake applied, the spring which is ordinarily employed to close the throttle pulls it rapidly closed and at the same time the bar 62 is effective to lift the float so that it is not permitted to move to a 55 relatively wide open position on the sudden surging forward of the fuel within the float chamber, which occurs when the vehicle is stopped suddenly.

55 While the form of embodiment of the present invention as herein disclosed, constitutes a preferred form, it is to be understood that other forms might be adopted, all coming within the scope of the claims which follow.

What is claimed is as follows:

75 1. A carburetor for internal combustion en-

gines comprising a mixture passage, means for supplying fuel and air thereto, a throttle for regulating the flow through said mixture passage, and means operated by the throttle as said throttle is moved toward closed position and before the throttle reaches fully closed position to prevent enriching of the mixture during deceleration.

80 2. A carburetor for internal combustion engines comprising a mixture passage, means for supplying fuel and air thereto, a throttle for regulating the flow through said mixture passage, a fuel reservoir, and means operated by the throttle to restrict the flow of fuel to the fuel reservoir as said throttle is moved toward closed position but before it reaches fully closed position, whereby the flow of fuel to the reservoir is restricted but not entirely prevented so that the engine can continue to operate.

85 3. A carburetor for internal combustion engines comprising a mixture passage, means for supplying fuel and air thereto, a throttle for regulating the flow through said mixture passage, a fuel reservoir, a float therein adapted to control the admission of fuel to said fuel reservoir, and means for moving said float to a 90 position to restrict the admission of fuel to said reservoir as said throttle is moved toward closed position and before the throttle reaches fully closed position to prevent enriching of the mixture during deceleration.

95 4. A carburetor for internal combustion engines comprising a mixture passage, means for supplying fuel and air thereto, a throttle for regulating the flow through said mixture passage, a fuel reservoir, a float therein adapted to control the admission of fuel to said reservoir and positioned to one side of the axis of said reservoir, whereby on deceleration the level of fuel beneath the float tends to fall, and means engaging the float to hold it in position to restrict the admission of fuel to the fuel reservoir, on lowering of the fuel level beneath the float during deceleration.

100 5. A carburetor for internal combustion engines comprising a mixture passage, means for supplying fuel and air thereto, a throttle for regulating the flow through said mixture passage, a fuel reservoir, a float therein adapted to control the admission of fuel to said reservoir and positioned to one side of the axis of said reservoir, whereby the fuel level beneath the float tends to fall on deceleration and means operated by the throttle on movements thereof toward closed position to engage the float so as to hold it in position to restrict the admission of fuel to the fuel reservoir, on lowering of the fuel level beneath the float during deceleration.

105 6. A carburetor for internal combustion engines comprising a primary carbureting device for supplying a primary mixture of fuel and air to a secondary mixing chamber in which said primary mixture may be mixed with additional air, means for supplying fuel and air to said primary mixture passage, a primary throttle regulating the flow therethrough and means operated by the primary throttle as said throttle is moved toward closed position and before it reaches fully closed position in order to prevent enriching of the primary mixture during the period of deceleration.

110 7. A carburetor for internal combustion engines comprising a primary carbureting device for supplying a primary mixture of fuel and air to a secondary mixing chamber, in which said

115

primary mixture may be mixed with additional air, means for supplying fuel and air to said primary mixture passage, a primary throttle regulating the flow therethrough, a fuel reservoir and means operated by the primary throttle as said throttle is moved toward closed position and before it reaches fully closed position in order to restrict the flow of fuel to said reservoir during periods of deceleration accompanying closing movements of the throttle.

8. A carburetor for internal combustion engines comprising a primary carbureting device for supplying a primary mixture of fuel and air to a secondary mixing chamber, in which said primary mixture may be mixed with additional air, means for supplying fuel and air to said primary mixture passage, a primary throttle regulating the flow therethrough, a fuel reservoir, a float therein adapted to control the admission of fuel to said reservoir and means engaging the float and operated by the primary throttle to move said float to a position to restrict the admission of fuel to said reservoir on movements of said throttle toward closed position and before the throttle reaches fully closed position.

9. A carburetor for internal combustion engines comprising a mixture passage, means for supplying fuel and air thereto, a throttle for regulating the flow through said mixture passage, a fuel reservoir, a float therein adapted to control the admission of fuel to said reservoir, means to move the float to a position to restrict the flow of fuel to the reservoir during the movement of the throttle toward closed position, said means comprising a member movable with the throttle in a generally vertical direction and a bar extending from said member to a position beneath the float.

10. A carburetor for internal combustion engines comprising a mixture passage, means for supplying fuel and air thereto, a throttle for regulating the flow through said mixture passage, a fuel reservoir, a float therein adapted to control the admission of fuel to said reservoir, a fuel pump operable by the throttle on opening movements thereof to supply additional fuel to the mixture passage during the acceleration period and means operated by said pump to restrict the admission of fuel to the reservoir during the

movement of the throttle toward closed position, to prevent enrichment of the mixture during deceleration.

11. A carburetor for internal combustion engines comprising a mixture passage, means for supplying fuel and air thereto, a throttle for regulating the flow through said mixture passage, a fuel reservoir, a float therein adapted to control the admission of fuel to said reservoir, a fuel pump operable by the throttle on opening movements thereof to supply additional fuel to the mixture passage during the acceleration period, means operated by the pump to move the float to a position to restrict the flow of fuel into the fuel reservoir during the movement of the throttle toward closed position to prevent enrichment of the mixture during deceleration.

12. A carburetor for internal combustion engines comprising a mixture passage, means for supplying fuel and air thereto, a throttle for regulating the flow through said mixture passage, a fuel reservoir, a float therein adapted to control the admission of fuel to said reservoir, a fuel pump operable by the throttle on opening movements thereof to supply additional fuel to the mixture passage during the acceleration period, a pump operating member extending from the pump to the throttle and adapted to be reciprocated in a substantially vertical plane as the throttle is opened and closed, and a bar extending from said member to a point beneath the float, whereby said bar is adapted to move the float toward closed position as the throttle is moved toward closed position.

13. A carburetor for internal combustion engines comprising a mixture passage, means for supplying fuel and air thereto, a throttle for regulating the flow through said mixture passage, a fuel reservoir, a float therein adapted to control the admission of fuel to said reservoir, a fuel pump adapted to supply additional fuel to the mixture passage, to enrich the mixture during the acceleration period, and a single means effective to operate said pump as the throttle is opened, and to operate the float to restrict the admission of fuel to the reservoir as the throttle is moved toward closed position.
